ADDITIVE INJECTING AND BLENDING APPARATUS FOR FILAMENT SPINNING

William P. Dooley, Wallingford, Pa., assignor to American Viscose Corporation, Philadelphia, Pa., a corporation of Delaware

Filed Apr. 25, 1957, Ser. No. 655,055

4 Claims. (Cl. 259—9)

This invention relates to liquid injection and blending apparatus, and more particularly to a device for injecting a secondary stream of additive-containing viscose into a primary stream of viscose and thoroughly blending the mixture prior to spinning. This case is related to Serial No. 477,904, filed December 27, 1954, now Patent No. 2,798,698, same assignee.

The problems connected with the injection of one stream of a liquid such as viscose into a second viscose stream are, to a considerable extent, influenced by the nature of the liquid itself. Such problems have to do with the elimination of dead spots where the viscose may become stagnant or may have a tendency to set up. In addition the viscous nature of the fluid may cause a considerable pressure drop through the blending apparatus. This condition is highly undesirable since it requires one or more booster pumps in the line. The very nature of viscose is such that the injected stream tends to resist complete mixing and therefore relatively violent agitation and blending is required to achieve homogeneity.

A primary object of the invention therefore is to provide a combined injection apparatus and blender which is highly efficient in its blending action and leaves no stagnant zones.

A still further object of the invention is to provide an improved injection blender having a two-stage blending element mounted on a common shaft, the first stage comprising a high speed agitator of relatively small diameter and the second stage comprising a series of rotors and stators of relatively larger diameter. A more concise object is to improve the preliminary disperser described in Patent No. 2,798,698.

Further objects will be apparent from the specification and drawings in which:

Figure 1 is a flow diagram showing the pre-blender of this invention in place in a viscose spinning system;

Figure 2 is an enlarged sectional view of the injection blending device of this invention;

Figure 3 is a front view of the wiper rotor used in the construction of Figure 2; and

Figure 4 is an isometric view of one of the rotors of Figure 2.

The invention comprises essentially the provision of a cylindrical housing having two mixing or blending zones in series, the first zone employing a novel wiper rotor, and the second a plurality of alternating stator and rotor elements mounted along its axis. The liquids to be blended flow axially through the rotor and stator elements and the rotor discharges the mixture of primary and secondary liquids tangentially through a discharge port at right angles to the axis of the rotor shaft. The secondary or additive stream is delivered to the preliminary mixing zone immediately in front of the stators and rotors. The rotor shaft at a point within this premixing zone is provided with the wiper rotor which functions as a preliminary stirring element to initially smear the additive stream into a circular ring within the main viscose stream before the latter enters the rotor-stator mixing zone.

2

Referring to Figure 1, a stream of viscose passes through line 10 to a final blender 17. A portion of the viscose is metered off from line 10 through shunt line 12 into pre-blender 14 wherein it is mixed with a stream of additive from line 13. The resulting blended stream of viscose and additive (seed viscose) is metered through metering pumps 15 and line 16 which draw more liquid than is supplied through line 12, so that the difference is made up by the additive drawn in through line 13. The seed viscose stream is pumped into final blender 17 wherein it is injected into and mixed with the main viscose stream from line 10. The final blend from blender 17 is passed through line 18 to suitable spinning means. This system as described is of primary use when the additive from line 13 is an abrasive pigment dispersion; such an additive would cause severe wear and abrasion on metering pumps 15 if the additive was not dispersed to some extent in the viscose; this is the function of pre-blender 14. This basic system is covered in applicant's copending application Serial No. 474,154, filed December 9, 1954 now abandoned.

Referring to Figure 2, pre-blender 14 is contained in a cylindrical housing 20 which has an inlet flanged coupling 21 through which the primary stream enters the housing via orifice 22. The secondary stream from line 13 is injected into the main stream through injector 23. Wiper rotor 25, mounted on shaft 26, continuously rotates past the nipple of nozzle 23 so as to immediately begin dispersing the additive into the viscose as soon as it enters the blender. This prevents the formation of crusts and agglomerates of pigment at the entry point. It also prevents the formation of viscose gels when the additive is of limited compatibility in viscose, such as polyvinyl alcohol or Pycal (4-dendrophenol). These have low solubility with viscose. The clearance between the top of injector 23 and the periphery of wiper 25 is slight, on the order of $\frac{1}{16}$ inch; the wiper should pass as close to the injector tip as possible since its purpose is to wipe the additive from the injector outlet and to spread the additive in a thin film at high speed.

As seen in Figure 3, wiper rotor 25 is in the form of a cup-shaped member having curved fingers 25a extending toward the orifice 22. The curved fingers 25a form an interrupted cylindrical surface which lies close to the discharge of nozzle 23. Wiper 25 is secured to shaft 26

(Figure 2) by key 27 which fits keyway 25b of the wiper, and is tightened to the shaft by nut 29.

The secondary blending stages comprise a series of rotors 30, 30a, 30b and alternating stators 40, 40a. The rotors are keyed to shaft 26, which in turn is supported in bearing sleeve 28, the latter being seated in recessed flange 21a. Each stator 40, 40a contains a series of perforations 41 preferably arranged in concentric rows to permit passage of the liquid and to break up the initially mixed streams into relatively fine filaments. Each stator is centrally recessed to permit sufficient clearance for key 27 on shaft 26 to clear the stators during rotation.

The final rotor 30b is in line with the axis of discharge fitting 45, which is at right angles to the axis of the rotors and shaft. In this way the rotor 30b functions, in addition to its mixing action, as a centrifugal pump to boost the discharge pressure from the blender and thus eliminate the necessity for installing a secondary booster pump in the line should the pressure drop be considered excessive. This tangential rather than axial outlet also permits the entire shaft and rotor assembly to be carried in very adequate outboard supports. All rotors are of identical construction (Figure 4). Each rotor has a solid hub that is keyed to shaft 26, and the periphery of the rotors comprises a plurality of spokes 33 having a substantially rectangular cross-section. In addition to the spokes, I provide two or more vanes or paddles 34 spaced 120°

apart which act as shear elements to vigorously break up and mix the individual streams delivered through the perforations of the stators. Using a small rotor of this type, e.g., two inches in diameter, a three-vaned rotor is about the optimum for good shearing and mixing action since the smaller the rotor shaft diameter the smaller is the number of vanes that can practically be installed. Also the less paddles the less the horsepower required to maintain a given speed. It is more efficient to run a big blender at low speed than a small one at high speed.

The wiper rotor 25 is an improvement over the "dispersator" employed at the corresponding position in applicant's copending application Serial No. 477,904 now Patent No. 2,798,698 in that it has a predictable capacity at various speeds. The dispersator of that application loses proportional capacity at low speeds and tends to act as a solid body at high speeds in high viscosity viscose. The contribution to capacity of the blender by wiper rotor 25 is at least twice that of the said dispersator.

In a typical embodiment of the invention final blender 17 has an inner diameter of four inches, has four rotors and three stators and the wiper rotor, and operates at 1800 r.p.m., which results in a capacity of 40 gallons per minute; pre-blender 14 has a two-inch inner diameter, three rotors and two stators and the wiper rotor, and when operated at 1800 r.p.m. has a capacity of about 9 gallons per minute. The speed of the pre-blender 14 is adjusted independently of the final blender 17 to give the desired pre-blender capacity. The percent of additive injected varies widely according to what the additive is and the effect desired, whether pigment or other viscose chemical additives. For example in the spinning of a pale pink colorspun rayon yarn as compared to a black colorspun yarn the ratio of pink pigment to carbon black is 1:2,000. Also a small denier filament requires more pigment than a large denier filament to attain the same degree of color. Thus, in spinning 100 pounds of a 15 denier yarn as compared to spinning 100 pounds of a 1.5 denier yarn of the same color it is necessary to use about three times as much pigment for the finer denier. Hence all of these factors must be taken into consideration in adjusting the blenders for each run.

The combined injection blender, as described above, is admirably suited for use with relatively thick viscous liquids such as viscose. It is simple, effective, and the two stages provide exceptionally effective blending for the addition of any desired secondary fluid. As illustrated above, this is preferably an additive intended to accomplish an improved physical characteristic in the extruded filaments, such as a delustrant or a pigmented mixture for yarn coloring. This does not exclude such additives as

surfactants or "greening agents" used in high strength yarns and fibers whereby the process is simplified, resulting in economic advantage or in commercial practicality. Depending upon the particular installation, the design 5 may be modified to operate as a booster pump if the elimination of pressure drop through the device is important. Low cost, adequate capacity and elimination of stagnant areas together with very complete blending are important features of the design.

10 I claim:

1. An injection blender for viscous material comprising a cylindrical housing, means for admitting a viscous liquid into one end of said housing, an injector extending through said housing near the end where the viscous liquid is admitted for introducing an additive liquid, said injector having an opening directed toward the axis of said housing, a discharge port in said housing axially removed from the points of admission of the liquids, a rotatable shaft extending through the other end of said housing, a first stage agitator secured to said shaft within said housing, said agitator comprising a cup-shaped member having curved fingers extending axially toward the point of admission of the viscous liquid, said curved fingers forming an interrupted cylindrical surface which lies close to and directly in line with the opening of said injector so that as said agitator rotates the additive liquid is wiped into and dispersed in the viscous liquid, and a second stage agitator in said housing between said first stage agitator and said discharge port, said second stage 20 agitator comprising a plurality of rotors mounted on said shaft and a plurality of stationary perforated plates located between said rotors, the rotors and stationary plates being arranged with a rotor ahead of each plate.

2. The apparatus set forth in claim 1 wherein one of 25 the rotors of said second stage agitator is located directly adjacent said cup-shaped member.

3. The apparatus set forth in claim 1 wherein said rotors have a diameter only slightly less than the internal diameter of said cylindrical housing.

4. The apparatus set forth in claim 1 wherein said discharge port extends radially through said housing.
